CLAIM

The ornamental design for a bathroom accessory holder, as shown and described.

DESCRIPTION

FIG. 1 is a top plan view of a bathroom accessory holder showing our new design as embodied in a soap dish;

FIG. 2 is a right side elevational view thereof, the left side being a mirror image;

FIG. 3 is a front elevational view thereof;

FIG. 4 is a rear elevational view thereof;

FIG. 5 is a vertical cross-sectional view thereof, taken along line 5—5 of FIG. 1;

FIG. 6 is a top plan view of an alternative embodiment thereof, as embodied in a combined toothbrush and tumbler holder;

FIG. 7 is a right side elevational view of the embodiment of FIG. 6, the left side being a mirror image;

FIG. 8 is a front elevational view of the embodiment of FIG. 6;

FIG. 9 is a rear elevational view of the embodiment of FIG. 6; and,

FIG. 10 is a vertical cross-sectional view of the embodiment of FIG. 6, taken along line 10—10 of FIG. 6.

fig. 1.

fig. 2.

fig. 3.

fig. 4.

fig. 5.

FIG. 6.

FIG. 7.

FIG. 8.

FIG. 9.

FIG. 10.
